(57) **CLAIM**

The ornamental design for a headlamp cover lens, as shown and described.

DESCRIPTION

FIG. 1 is a perspective view of a headlamp cover lens showing our new design;

FIG. 2 is a top view of the headlamp cover lens;

FIG. 3 is a front view of the headlamp cover lens;

FIG. 4 is a left side view of the headlamp cover lens; and, FIG. 5 is a right side view of the headlamp cover lens.

The bottom of the headlamp cover lens is unornamented.

FIGS. 1-5 illustrate a first embodiment of our novel design suitable for use on the driver's side of a tractor-trailer. Our novel design also includes a second embodiment suitable for use on the passenger side of the vehicle which is mirror symmetrical to FIGS. 1-5 and therefore not separately illustrated.

The flange shown in broken line in FIGS. 1, 2, 4 and 5 is for purposes of illustration and forms no part of the claimed design.
